L. W. KAESTNER.
ARTICLE CARRIER.
FILED AUG. 9, 1920.

Inventor:
Louis W. Kaestner,

By Sheridan, Jones, Sheridan & Smith
Atlys.

UNITED STATES PATENT OFFICE.

LOUIS W. KAESTNER, OF CHICAGO, ILLINOIS.

ARTICLE CARRIER.

Application filed August 9, 1920. Serial No. 402,888.

To all whom it may concern:

Be it known that I, LOUIS W. KAESTNER, a citizen of the United States, residing at Chicago, in the county of Cook and State 5 of Illinois, have invented certain new and useful Improvements in Article Carriers, of which the following is a specification.

This invention relates to improvements in article carriers and is an improvement upon 10 the device shown in my prior United States Patent No. 1,295,174, patented February 25, 1919.

The object of this invention is to provide an article carrier in which the article 15 loops are adjustable to various dimensions and in which the loop will remain of proper size except when it is desired to change the same.

Still another object consists in the provision of such a device with slidably mounted cross strips coacting with the main straps mounted in suchwise as to be removable, when desired, from the mounting upon 20 which they slide.

25 These and other objects will be more fully described and set forth in the following specification and shown in the accompanying drawings in which—

Fig. 1 is a front elevation of one embodiment of my invention;

Fig. 2 is a transverse section on the line 2—2 of Fig. 1;

Fig. 3 is a vertical section on the line 3—3 of Fig. 1;

35 Fig. 4 is a similar section on the line 4—4 of Fig. 1.

Like numerals denote like elements throughout the drawings, in which—

10 indicates generally the main carrier board and 24 designates the slidable cross-strips, mounted to slide upon the strip 23 which is superimposed upon the strip 20, being spaced therefrom from the interposed narrow strip 21. The free ends of the cross-strips 24 are inwardly turned, as indicated 40 by numeral 24^a, to slide in the groove between strips 20 and 23.

30 designates the main holding straps which coact with the cross-strips 24 to form 50 the holding loops through which the articles to be held are inserted.

The cross-strips 24 are so formed with respect to the strips 23 and straps 30 that they will frictionally engage and press the straps 55 30 against the strips 23 as I have endeavored

to indicate in Fig. 4. I find that by this engagement, upward pull on the straps 30 from the inserted articles will not operate to shift the strap and enlarge the openings even if some of the loops be unfilled. It frequently occurs in the use of these devices that some of the articles are removed whereupon the filled loops become enlarged, allowing the articles therein to drop out. In this invention, this is obviated as explained 60 above. At the same time the frictional contact is such that when the strap 30 is flattened upon the strip 23 and pushed by the user, it will slide through the cross-strips 24 to adjustable position or, if such sliding is 65 difficult, it is merely necessary to grip the ends of the cross-strips 24 between the fingers to eliminate the frictional contact.

It sometimes becomes necessary and advisable to remove some of the cross strips 24 70 to vary the number of loops used or for other reasons and to permit this, I provide pivoted cross-bars 35 at the open ends of the grooves formed between the strips 20 and 23, as shown in Figs. 1 and 3. These cross-bars 75 35 may be pivoted to the position shown in dotted lines in Figs. 1 and 3 to provide removal of the cross-strips 24, the spacing strips 21 terminating at 21^b to permit this 80 pivotal movement.

85 It is believed that the operation of my device is sufficiently clear from my description. It is also obvious that my invention is susceptible to numerous modifications and applications and I do not wish to be restricted 90 to the form described except as defined in the appended claims.

What I claim is—

1. In a device of the class described, a main strip, a plurality of strap engaging cross-strips slidable upon said first named strip, and means to prevent disengagement of said cross-strips with said main strip, said means being operable to permit removal of said cross-strips.

100 2. In a device of the class described, a main strip, a plurality of strap engaging cross-strips slidable upon said first named strip, and means to prevent disengagement of said cross-strips with said main strip, said means comprising a pivoted cross-bar.

105 3. In a device of the class described, a pair of superimposed main strips, said strips being secured in spaced relation to provide grooves therebetween, strap engaging cross- 110

strips slidably mounted on one of said main strips, and a cross-bar pivoted between said main strips.

4. In a device of the class described adjustable article holding members, supporting members positioned therebeneath, means movable with respect to and engaging said supporting members and adjustably securing

said holding members thereon, and pivoted means operable to permit the disengagement of said securing means from said supporting members.

In testimony whereof, I have subscribed my name.

LOUIS W. KAESTNER.
